SAFETY RAZOR

Herman H. Kempf, Brooklyn, and Charles L. Woody, Port Jefferson, N. Y.

Application August 12, 1937, Serial No. 158,648

11 Claims.

(Cl. 30—62)

This invention relates to improvements in safety razors, and more particularly to the holder for the cutting blade.

The construction of the holder is such that it can be readily formed from a single thin sheet of material, preferably metal. Said construction is such that there is ease in the insertion and detachment of the blade and security in its attachment. The holder is adapted for use with a double-edged blade of the wafer type.

Other objects and advantages will become apparent upon a further study of the description and drawing, in which:

Fig. 1 is a perspective view of the holder with a cutting blade in it.

Fig. 2 is a partial section, to an enlarged scale, taken along the line 2—2 of Fig. 1.

Fig. 3 is a plan view, to an enlarged scale, of the supporting plate without the blade.

Fig. 4 is a partial section taken along the line 4—4 of Fig. 3, and

Fig. 5 is a plan view, to an enlarged scale, of the supporting plate with a blade mounted on it.

The blade-supporting member or plate 6, has a wide tongue 7 struck up from it, the root of the tongue being along a longitudinal line substantially parallel to the front edge of plate 6, and located at substantially the mid-portion of said plate. The forward portion of tongue 7 is above the plane of plate 6. The portion of the tongue immediately adjacent its front edge is bent upward from the plane of the tongue. While a single wide tongue is our preferred form, instead of it, there could be used a row of two or more similar but narrower tongues similarly situated to replace it. Slightly forward of the root or springing line of tongue 7, and on either side of it, plate 6 has projections 8 extending upward therefrom. Projections 8 are preferably humps with rounded tops pressed up from plate 6. Said projections are on a longitudinal line substantially parallel to the front of plate 6.

Tongue 7 at its root is narrower than at the free end to allow humps 8 to be set in close enough to come within slot 18 of the blade.

The rear of plate 6 is bent up and forward in the form of a hook 9 to act as a rear guard for the rear cutting edge of blade 10. The front edge of plate 6 is curved downward and preferably serrated to form a guard 11. It is within the scope of my invention to use a front guard curved down as shown but without being serrated.

Looping downwardly and inwardly from each side of plate 6 and integral therewith is an arm 12. Each arm 12 at an interval below plate 6, is

provided with a front inturned flange 13 and a rear inturned flange 14. Arms 12 each have a bottom inturned flange 15. Arms 12 are tied to each other by an upper tongue 21 and a lower tongue 22. Said tongues are stamped out from the body of the arms, the tongue of one arm extending over to a slot 23 provided in the other and bent up to lie in a depressed portion 24 provided in said other arm.

Arms 12 each with its front flange 13 and rear flange 14 form a hollow handle substantially oblong in cross-section. Said handle is reversely curved in a slight S-shape for more conveniently gripping it by the fingers. The upper portion of the handle is convex to the rear at 16 and the lower portion is convex to the front at 17.

The type of blade most suitable for my holder is two-edged, flexible and thin. It is a wafer blade, like the well known "Gillette" or similar types. At the mid-portion of the blade is an elongated slot 18, well known in such blades. The irregularities of slot 18, as seen in Figs. 1 and 5, are those present in standard types of such blades and are not necessary for my holder. A long narrow slot having substantially straight and parallel sides would serve just as well.

In inserting the blade into the holder, the side edges 19 are gripped between the thumb and middle finger and the blade moved rearwardly from a position in front of plate 6 with the flat of the blade parallel to the flat of said plate, onto the top of said plate, engaging tongue 7 in slot 18 and forcing the forward edge of said slot under tongue 7. At the same time, the portions of blade 10 to the rear of slot 18 and near its right and left hand sides ride over humps 8. In passing over said humps, the rear of the blade is bent upward. As the blade is pushed to the rear, it is pinched between tongue 7, said tongue being resilient, and plate 6. When the forward edge of slot 18 is brought into abutment against the forward side of humps 8, blade 10 can no longer be pushed to the rear. When humps 8 enter slot 18, the rear portion of the blade unflexes. Tongue 7 presses down on the blade and holds the forward portion of the blade firmly down on top of plate 6.

To remove blade 10, it is gripped between the thumb and middle finger toward the rear of side edges 19. With the fingers in this position, the blade is pulled upon in an upward and forward direction, causing the rear edge of slot 18 to ride over humps 8 and the forward edge of said slot to come free from the pinching action of tongue 7.

While the holder is shown as made of one

piece of sheet material, and this is the preferred form, yet it could be made of several pieces fastened together. Instead of having tongue 7 struck up from plate 6, said tongue could be a separate piece of spring material fastened to said plate. Likewise humps 8 could be pieces added to plate 6, or said plate could be a casting with humps 8 formed on it and with the handle cast integral therewith.

10 While the claims specify a tongue for the sake of simplicity, we wish it to be understood that they are intended to be broad enough to cover the use of a row of two or more similar but narrower tongues to replace said tongue.

15 We claim:

1. A safety razor holder for use with a resilient wafer blade having an elongated longitudinal slot, said holder comprising a supporting plate, a cutting guard at the front of said plate, a resilient tongue connected at its rear to the plate and extending toward the front of the plate, and projections on said plate, the front of said projections being set back from the front of the plate so that when the front edge of the slot in the 25 blade is in engagement with the front of said projections, the cutting edge of the blade is in proper cutting position with respect to the guard, said tongue, with the blade in said position, extending through the slot and pressing down on the front portion of the blade.

2. A safety razor holder for use with a resilient wafer blade having an elongated longitudinal slot, said holder comprising a supporting plate, a cutting guard at the front of said plate, a resilient tongue connected at its rear to the plate and extending toward the front of the plate, and upwardly extending projections on said plate, the rear of said projections being set back from the front of the plate so that when the rear edge of 35 the slot in the blade is in engagement with the rear of said projections, the cutting edge of the blade is in proper cutting position with respect to the guard, said tongue with the blade in said position, extending through the slot and pressing down on the front portion of the blade, with the tongue so pressing, the rear of said projections normally prevents forward motion of the blade.

3. A safety razor holder for use with a resilient blade having an elongated longitudinal slot, said holder comprising a supporting member, a cutting guard at the front of said member, a resilient tongue connected at its rear to the member and extending toward the front of the member, and upwardly extending projections on said member, having a relatively wide longitudinal space between them, the front of said projections being set back from the front of the member so that when the front edge of the slot in the blade is in engagement with the front of said projections, the cutting edge of the blade is in proper cutting position with respect to the guard, the rear of 50 the projections being spaced from the front so that when the blade is in said cutting position, the rear edge of said slot engages said rear of the projections, normally preventing forward motion of the blade, said tongue, with the blade in said position, extending through the slot and pressing down on the front portion of the blade.

4. A safety razor holder for use with a resilient 70 blade having an elongated longitudinal slot, said holder comprising a supporting member, a resilient tongue connected at its rear to the member and extending toward the front of the member, the rear of said tongue being at a substantial distance back from the front of the member, and up-

wardly extending projections on said member being spaced longitudinally so that the distance across them from the outside of one to the outside of the other equals substantially the length of the slot, said projections being set back from the front of the member so that when they are in engagement with the slot, the cutting edge at the front of the blade is in proper cutting position with respect to the front of the member, said tongue, with the blade in said position, extending through the slot and pressing down on the front portion of the blade, thereby normally holding the latter from being raised off said projections.

5. In a safety razor, a blade-supporting member, a resilient wafer blade adapted to be carried thereby, said blade having an elongated longitudinal slot, a resilient tongue connected at its rear to the member and extending toward the front of the member, the rear of said tongue being at a substantial distance back from the front of the member, and upwardly extending projections on said member set back from the front of the member so that when the projections are in engagement with the slot, the cutting edge at the front of the blade is in proper cutting position with respect to the front of the member, said tongue with the blade in said position, extending through the slot and pressing down on the front portion of the blade, said blade being removable by pulling upon its side edges toward their rear, thereby flexing same, and moving it forward to ride over the projections and to slide out from under the tongue.

6. In a safety razor, a blade-supporting member, a resilient wafer blade adapted to be carried thereby, said blade having an elongated longitudinal slot, a resilient tongue connected at its rear to the member and extending toward the front of the member, the rear of said tongue being at a substantial distance back from the front of the member, and upwardly extending projections on said member set back from the front of the member so that when the projections are in engagement with the slot, the cutting edge at the front of the blade is in proper cutting position with respect to the front of the member, said tongue, with the blade in said position, extending through the slot and pressing down on the front portion of the blade, said blade being insertible by 40 grasping it at its side edges and moving it rearward over said member, causing the tongue to pass through the slot and come over the forward portion of the blade, the rear portion of the blade flexing upward and riding over the projections as the tongue passes over said front portion, said blade unflexing at its rear when the projections have entered the slot.

7. A safety razor holder for use with a resilient blade having an elongated longitudinal slot, said holder comprising a supporting member, a resilient tongue connected at its rear to the member and extending toward the front of the member, the rear of said tongue being at a substantial distance back from the front of the member, the tongue near its front edge curving upwardly and away from the top face of the member to permit the ready insertion of a blade between the tongue and the member, and projections extending upwardly from said face, said projections being set back from the front of the member so that when they are in engagement with the slot, the cutting edge at the front of the blade is in proper cutting relation to the front of the member.

8. A safety razor holder for use with a resilient

blade having an elongated longitudinal slot, said holder comprising a supporting member, a resilient tongue connected at its rear to the member and extending toward the front of the member, the rear of the tongue being at a substantial distance back from the front of the member, and an upwardly extending projection on said member alongside each side of the tongue, said projections being spaced longitudinally so that the distance across them from the outside of one to the outside of the other equals substantially the length of the slot, said projections being set back from the front of the member so that when they are in engagement with the slot, the cutting edge at the front of the blade is in proper cutting relation to the front of the member, said tongue, with the blade in said relation extending through the slot and pressing down on the front portion of the blade, the width of the tongue at its front being greater than where it comes between said projections.

9. A safety razor holder for use with a resilient double cutting edged blade having an elongated longitudinal slot, said holder comprising a supporting member, a cutting guard at the front of said member, the rear of said member having an upwardly and forwardly extending flange, a resilient tongue connected at its rear to the member and extending toward the front of the member, the rear of the tongue being at a substantial distance back from the front of the member, and upwardly extending projections on said member set back from the front of the member so

that when they are in engagement with the slot, the front cutting edge of the blade is in proper cutting position with respect to the guard and the rear cutting edge is out of contact with said flange, said tongue, with the blade in said position extending through the slot and pressing down on the front portion of the blade. 5

10. In a safety razor, a one-piece sheet metal holder comprising a supporting plate, means formed on said plate for retaining a cutting blade thereon, an arm extending inwardly and downwardly from each side of said plate, said arms at their lower portions being channel-shaped with webs parallel and flanges extending toward each other and meeting, said webs extending in a front to rear direction, and means for fastening the arms to each other. 10

15. In a safety razor, a one-piece sheet metal holder comprising a supporting plate, means formed on said plate for retaining a cutting blade thereon, an arm extending inwardly and downwardly from each side of said plate, said arms at their lower portions being channel-shaped with webs parallel and flanges extending toward each other and meeting, said webs extending in a front to rear direction, and a tongue struck from the web of one arm and extending through a corresponding slot in the other and bent to prevent its removal therefrom, for fastening the arms to each other. 15
